JOSEPH L. KLEIN, OF TWO RIVERS, WISCONSIN.

PACKAGE-TIE.

1,320,765.

Specification of Letters Patent.

Patented Nov. 4, 1919.

Application filed August 12, 1918. Serial No. 249,536.

To all whom it may concern:

Be it known that I, JOSEPH L. KLEIN, a citizen of the United States, and resident of Two Rivers, in the county of Manitowoc 5 and State of Wisconsin, have invented certain new and useful Improvements in Package-Ties; and I do hereby declare that the following is a full, clear, and exact description thereof.

10 My invention relates to new and useful improvements in tying means for the fastening cords of packages, and more particularly of that type employed by postmen or other persons for temporarily securing bundles of 15 letters or other articles. My invention resides in the provision of an improved fastening member and of an improved method of manipulating a fastening cord in connection with the fastening member to procure a 20 binding holding of various parts of the cord without the necessity of knotting the cord.

It is the object of my invention to increase the rapidity and convenience with which a 25 tying operation of this nature may be carried out.

A more specific object resides in the provision of an improved fastening member adapted for permanent connection with one 30 end of the tying cord, and having its other parts so arranged for tying co-action with the cord that the fastening member may be placed on the package and pressed thereagainst by one of the fingers of the operator's 35 hand continuously during the entire binding and tying operation, whereby to permit a maximum convenience and rapidity of the tying operation.

With the above and other objects and advantages in view, my invention resides more 40 particularly in the novel combination and arrangement of parts, hereinafter described and pointed out in the appended claims.

In the accompanying drawings:

Figure 1 is an enlarged plan view of my 45 improved fastening member and the tie procured in conjunction therewith.

Fig. 2 is a sectional view on the line 2—2 of Fig. 1.

Fig. 3 is a plan view of a package having 50 my improved device associated therewith, and showing an intermediate step of the tying operation.

Fig. 4 is a plan view similar to Fig. 3, of a modified form of tie member.

55 Fig. 5 is a detailed enlarged view showing the binding actions on the cord stretches.

Referring now more particularly to the accompanying drawings, a preferred embodiment of my fastening member comprises a hook-shaped body formed of a flat 60 plate of metal and comprising a bill portion 5, a bight portion 6 and a shank portion 7, the shank portion being extended a considerable distance past the end of the bill portion, and the bill portion being inclined 65 slightly outward from the shank portion and reduced in plan toward its free end whereby to facilitate the insertion of a cord thereunder. The bight portion 6 is widened, 70 whereby its external contour is eccentric to its internal contour to prevent a loop of cord disposed about the inner end of the shank from slipping around the bight portion. The shank 7 terminates in an inwardly offset eye 8, through which is passed the cord 75 member 9, normally permanently retained in the eye 8 by a knot 10 on its end. A finger piece is provided at the outer portion of the shank, and in the present instance this finger piece is in the form of a ring-like projection 80 11 on the plate body, the sides of which merge into the eye 8 and into the intermediate portion of the hook shank. By offsetting the eye 8 inwardly, it is noted that the aperture of said eye is substantially in alignment with the bight space of the hook longitudinally of the shank, and it is further noted that the inner edge of the hook bill 5 is concave adjacent the bight.

I shall now describe the method of forming the tie in connection with this form of fastening member, although it will be appreciated that the improved method may be carried out in its broader aspect in conjunction with any hook-shaped body having a 95 cord fastening means at one end of its shank. Referring more particularly to Fig. 3, the fastening member is placed on an intermediate portion of the top surface of the package A and is pressed thereagainst by engagement of the thumb B of the left hand of the operator on the finger piece ring 11. The cord 9, manipulated by the right hand, is then wrapped transversely about the package to form a loop terminating in a stretch 100 r on the top surface of the package, it being appreciated however, that a plurality of these loops may be provided if desired. The cord is then inserted under the bill 5 and extended in a right-angular direction 110 across the shank 7 and looped about the package in that direction, this loop termi-

nating in the stretch *t* on the top of the package, this stretch being also brought under the bill 5. The cord, by the aid of the second finger C of the left hand is then 5 formed into a loop *u* by being merely extended around the finger and the free stretch of this loop, terminating in the final stretch *v* of the cord which is grasped and manipulated by the fingers D of the right hand, is 10 also brought under the hook bill 5, the finger C pressing the loop against the top of the package and holding it against looseness. The cord stretch *v* is then drawn to draw the loop tightly to the inner end of the 15 hook shank, the finger C releasing the loop under pressure as it is thus drawn. In this drawing movement, the portion of the loop at the outer side of the shank obviously is drawn under the juncture of the cord 20 stretches *r* and *s*, which are under considerable tension, the loop being prevented from slipping about the bight by the widening thereof heretofore mentioned, although it will be appreciated that there is slight 25 tendency for this slipping action to cause any looseness of the tie.

The foregoing described tying operation may be most readily carried out by any person without necessitating the development of a considerable amount of skill by 10 continued practice, this being a disadvantage of various types of fasteners heretofore proposed, and by the plurality of binding actions procured on the cord, the tie 15 member will hold efficiently even under adverse conditions imparting various stresses upon the cord and fastener. The loop *u* is in frictional engagement throughout with the fastener shank and as shown particularly in 20 Fig. 5, the juncture of the loop *u* and the cord stretch *v* is decidedly pinched by the juncture portion of the loop *u* with the cord stretch *t*, and both stretches of the loops as 25 well as these two juncture portions mentioned are engaged and pinched by the juncture portion of the cord stretches *r* and *s*. These binding actions are also shown in 30 Fig. 2, wherein the juncture portion of the stretches *r* and *s* is shown pressing the adjacent cord portions against the inner edges 35 of the hook shank and bill. A further point is noted that the knot 10, as well as 40 cord portions which are engaged under the tie member in intermediate steps of the tying operation, serve as fulcrums upon 45 pressure of the finger upon the finger piece 11, whereby the bill 5 of the hook is rocked 50 upwardly to facilitate engagement of the cord thereunder in the formation of the various loops described. In Fig. 4, a modified 55 form of fastener member is provided, wherein the bill portion 5' of the hook member is substantially equal in length to the shank member 7', this shank member being merged 60

into an elongated flat finger piece 11' which 65 extends obliquely outward to a point rearwardly of the hook, the juncture of this finger piece 11' and the bight portion 6' of the hook forming a shoulder 12 which is disposed rearwardly of the inner edge of the 70 hook bight. Thus, in the formation of the loop *u*, it is disposed and held by the shoulder 12 in decidedly oblique relation to the stretch *t*, which provides the direct tension 75 on the loop, and thus the juncture of the loop *u* and stretch *t* exerts a more positive binding action on the juncture of the loop *u* and stretch *v* independent of and co-incident with the binding action of the juncture of the stretches *r* and *s*. 80

I have thus shown two embodiments of my tie member. It will be, however, appreciated that various embodiments thereof may be employed to meet differing conditions of use, and that the tie member may be 85 formed of wire. The essential feature of the tie member is a hook-shaped body having means at one end of its shank for securing a cord thereto, and having its bight portion adapted for the cord tying manipulations set forth, a further feature of importance being the provision of a finger 90 piece on the outer side of the shank.

What is claimed is:

1. A tie member comprising a shank, a hook at one end of the shank, a securing eye at the other end of the shank, and a finger piece projecting from the shank at its side remote from the bill of the hook, the major portion of said finger piece being disposed intermediately of the hook and the securing eye, said finger piece being engageable by the finger of the operator to press said finger piece against the surface of a package to be tied whereby to prevent relative movement of the tie member. 95

2. A tie member comprising a plate shaped to form a shank, and a hook portion at one end of the shank, the other end of the shank being apertured to form a securing eye, the bight portion of the hook being wider than the adjacent portion of the shank whereby to prevent movement about the bight portion of the tie loop disposed around the adjacent shank portion, and a finger piece projecting from the side of the shank remote from the bill of the hook, the major portion of said finger piece being disposed intermediately of the hook and the securing eye, said finger piece being engageable by the finger of the operator to press said finger piece against the surface of a package to be tied whereby to prevent relative movement of the tie member. 100

3. A tie member having a hook-shaped body, means at the free end of the shank of the hook for securing one end of a tie cord thereto, a finger piece projecting from the 105

shank at its side remote from the bill of the hook, the bight portion of the body being wider than the adjacent portion of the shank whereby to prevent movement about the bight portion of a tie loop disposed around the adjacent shank portion, and a shoulder on the outer shank edge of the body member disposed rearwardly of the inner edge

of the bight with respect to the mouth of the hook.

10

In testimony that I claim the foregoing I have hereunto set my hand at Two Rivers, in the county of Manitowoc and State of Wisconsin.

JOSEPH L. KLEIN.
